UNITED STATES PATENT OFFICE.

MAX KÖHLER, OF LIMBACH, GERMANY.

OVERSEAMING MACHINE.

Application filed May 11, 1927. Serial No. 190,479.

The present invention relates to an improvement in overseaming machines. One object thereof has been to provide a machine in which the work supporting and feeding devices are so positioned that the operator may more freely have access thereto in placing and removing articles upon which work is to be done. Thus, in well known types of overseaming machines it is common to have the cylindrical feed cups supported upon suitable uprights underlying the respective cups so that, when a garment is placed in position between the cups, it is necessary for the operator to reach around the outer cup support in placing or removing the garment. Furthermore, this type of machine presents some difficulties in extremely rapid operation which it is believed will be overcome or minimized in a machine employing the features of construction embodied in my improved form of device. These and other advantages will become more apparent upon further consideration of the appended description and illustration of one form of my invention which is shown in the drawings wherein

Figure 1 is a front view,
Figure 2, a top plan view,
Figure 3, a detail section on the line 3—3
30 of Figure 2, and
Figure 4, a side view.

Referring to the drawings, an overseaming machine embodying my invention includes a housing 1 having a forwardly extending base 2. A main drive shaft 3 carrying a pulley 4 is journaled in the housing 1 and operates needle and loop actuating mechanism, not shown, but which may be of any suitable well known type. The shaft 3 carries an eccentric cam 5 and transmits endwise motion to a link 6 connected to said cam 5 by means of a strap 7. A lever 8 is pivotally mounted in the housing 1 at 9 and is connected at its upper end to the link 6 and at its lower end to a rod 10 which in turn actuates a suitable intermittent or step-by-step shaft feeding device 11, being connected thereto by means of a ball and socket joint 12, Figure 1. As indicated more clearly in Figure 4, an inner cylindrical feed cup 13 is secured to a shaft 14 driven by the intermittent feeding device 11. A gear 15 on said shaft 14 meshes with a gear 16 on an upright shaft 17 journaled at one end in a portion of the extension 2 and at the other

end in a bracket 18 secured to the upper part of the front wall of housing 1. The longitudinal axes of shafts 14 and 17 remain in fixed parallel relation. A gear 19 is mounted at the upper end of shaft 17 and preferably 60 within a suitable housing or box 20 supported on the bracket 18. In Figure 2, the box 20 is shown with the top or cover plate removed, while in Figure 4 a cover plate 21 is shown in operative position. A stud shaft 65 22 is journaled in the box 20 and carries a worm gear 23 in operative relation to the gear 19. At the outer end of shaft 22 and outside of box 20, I have provided a sleeve 24, the purpose of which will be described 70 in more detail in connection with the description of driving means for the other or outer cup 25 which cooperates with the cup 13 to retain articles in position for the overseaming operation and to feed said articles 75 step by step.

In the form of my invention illustrated in the drawings, the outer feed cup 25 is mounted so that it may be moved away from or toward the cooperating cup 13 in such a 80 way that the angular relation between the peripheral surfaces of said cups will not be altered. In well known forms of overseaming machines the outer cup is supported upon a tilting column so that, when said cup is 85 moved away from the inner cup, the central axis thereof will be disposed at an angle to the central axis of the inner cup. In my improved construction, the central axes of both cups remain parallel in all positions. 90

In order to support the outer cup in such a way as to produce the contemplated results, I provide a bracket 26 positioned at one side of the housing 1 and having a recess which affords spaced bearings for a slideable rod 27. 95 A head 28 is mounted on the forward end of said rod 27 and a guide and stop member 29 is secured to the rear end thereof and in position to be actuated by the free end of a bell crank lever 30 pivoted at 31 and actuated by any suitable means either manually or by foot power. In the illustrated form of device bell crank lever 30 is connected to suitable foot operated mechanism, not shown, by means of a link 32, a lever 33 and a link 34. 100 The recess in the enlarged portion of bracket 26 has a shoulder 35 against which is seated one end of a coiled spring 36 which surrounds a portion of rod 27. A collar secured to said rod 27 engages the other end of spring 36 110

so that the rod 27 and the head 28 are held normally in retracted position by reason of the expansion pressure of said spring 36. As indicated more clearly in Figure 1, the 5 guide and stop member 29 is provided with an open-ended slot 38, positioned to engage a guide rod 39 projecting rearwardly from the bracket 26. The slotted end of the member 29 engaging said rod 39 prevents tilting 10 or pivotal movement of the head 28. The member 29 also carries a set screw 40 which is movable to permit adjustment of the length of stroke of the rod 27. In other words, adjustment of the set screw 40 will permit a 15 greater or less movement of separation between the cups 13 and 25 depending upon the coarseness or fineness of the fabric or other article upon which the overseaming operation is to be performed.

20 Referring more particularly to Figure 2, the head 28 carries a box 41 shown in said figure with the cover removed and in Figure 4 with the cover 42 in operative position. One end of a stud shaft 43 is journaled in the front 25 wall of box 41 while the other end of said stud shaft 43 slidably engages the collar 24. For this purpose, the collar has a longitudinally extending slot 44 positioned to receive a 30 spline 45 secured to the stud shaft 43 by any suitable means such as bolts 46. Shaft 43 carries a worm gear 47 engaging a gear 48 mounted on a cup driving shaft 49 journaled in the head 28 and carrying at its lower end the outer cup 25.

35 In operation, the main shaft 3 is driven from any suitable source of power such as a motor and belt, not shown, engaging the pulley 4. To insert a knitted fabric or other article to be overseamed, the operator presses 40 down on a treadle mechanism, not shown, to deflect forwardly the lower or free end of the bell crank lever 30. This motion imparts sliding movement to the rod 27, thus carrying forward the head 28 and the driving 45 mechanism of cup 25 mounted thereon. The operator now has unobstructed access to the space between the feeding cups and can therefore readily and accurately position the fabric or other device to receive the overseaming 50 loops. It will be apparent that with free access as described, articles of considerable size and varied contour can be conveniently operated on, whereas in known types of machines of this character the space between the feed 55 cup supports quite definitely limits use of the machine in these respects. When foot pressure is released from the treadle, spring 36

presses rod 27 rearwardly and with it the head 28 and the cup 25, thus securing the article or fabric in feeding position between 60 said cup and the inner cup 13. The machine is now driven by main shaft 3 which operates the needle and loop mechanism in a known manner and through suitable connections also actuates the cups 13 and 25. Thus, reciprocal 65 movement is imparted to the rod 10 by means of the lever 8 which is operatively connected to the main shaft 3 as hereinabove described. This endwise to-and-fro motion of rod 10 is translated into intermittent rotation of the shaft 14 to which cup 13 is secured. Shaft 17 which at all times remains in parallel relation to shaft 14 is operatively connected to shaft 14 through gear 16 and transmits the step-by-step rotation of said 70 shaft to the stud shaft 22 from which said motion is in turn transmitted to the cup 25 by means heretofore described in detail.

75 It will be understood that the machine hereinabove described is also equipped with 80 suitable guiding devices for the articles to be overseamed as well as with thread tensioning devices and other suitable or necessary mechanical adjuncts usually or frequently found in machines of this character, although they form no part of the present invention and are therefore not separately 85 shown and described.

I claim as my invention:

In a sewing machine, the combination of 90 a housing, an inner feed cup, intermittent driving means for said inner cup, a bracket at one side of said housing, a cup supporting head slidably mounted in said bracket, an outer cup mounted on said head and movable 95 therewith toward and away from said inner cup, a casing at another side of said housing, a cross shaft in said casing, an upright shaft operatively connected with said intermittent driving means and with said cross shaft, an 100 outer cup driving shaft mounted in said cup supporting head, and a second cross shaft mounted in said head and operatively connected with said outer cup driving shaft, one 105 of said cross shafts being provided with a longitudinal slot and the other with a slot engaging lug to form a driving connection between said cross shafts at all operating positions of said outer cup relatively to said inner cup.

110 In testimony whereof, I have signed my name to this specification this 21 day of April, 1927.

MAX KÖHLER.
